UNITED STATES PATENT OFFICE.

WILLIAM S. EATON, OF SAG HARBOR, NEW YORK.

ENGRAVING-MACHINE.

SPECIFICATION forming part of Letters Patent No. 660,790, dated October 30, 1900.

Application filed August 8, 1900. Serial No. 26,232. (No model.)

To all whom it may concern:

Be it known that I, WILLIAM S. EATON, a citizen of the United States, and a resident of Sag Harbor, Suffolk county, State of New York, have invented certain new and useful Improvements in Engraving - Machines, of which the following is a specification.

This invention relates to an engraving-machine of the class called "routing-machines" and in which the engraving-tool is rotated so as to mill a groove into the work-piece. The machine is so constructed that the work-piece is movable in unison with the tracer, that power may be readily applied to the routing-tool, and that the depth of the groove cut into the work-piece is under the constant control of the operator.

In the accompanying drawings, Figure 1 is a plan of a gang-machine constructed according to my invention; Fig. 2, a vertical section on line 2 2, Fig. 1; Fig. 3, a sectional elevation taken on line 3 3, Fig. 1; and Fig. 4 a sectional elevation similar to Fig. 2, showing the parts in a different position.

The letter *a* represents the frame of the machine, having a horizontal bed-plate *a'*, which is provided with a pair of parallel grooves or rails *a*². These rails are engaged by the wheels or rollers *b'* of a lower carriage *b*, which on its upper face is provided with a pair of parallel grooves or rails *b*², extending at right angles to the rails *a*². The rails *b*² are engaged by the wheels or rollers *c'* of an upper carriage *c*, which is thus adapted to be moved horizontally in any direction.

Motion is imparted to the carriage *c* by means of a pivoted handle *d'*, which is adapted to be moved by hand. This handle is provided with the tracing-tool *d*, the point of which engages the pattern *A* to be reproduced and which is supported by a table *a*³. In order to hold the pattern in position, the table *a*³ is provided with a movable jaw *a*⁴, which engages a fin *A'* of pattern *A* and may be operated by screws *a*⁵.

The work-piece *B* on which the pattern is to be reproduced is adapted to be secured to the table *c*, so as to participate in its motion, it being held between a flange *c*² and a clamp *c*³, movable in a groove *c*⁴ of the table.

The machine may be either adapted for engraving a single work-piece or for engraving several work-pieces simultaneously, the drawings showing a gang-machine with three routing-tool spindles *e*. These spindles are mounted in bearings *e'* and are driven by a common belt *e*², running over guide-pulleys *e*³, cone-pulleys *e*⁴ on spindles *e*, and tension-pulleys *e*⁵.

The bearings *e'* are clamped to a rock-shaft *f*, hung across the upper carriage *c* and oscillating on centers *f'*. The rock-shaft *f* is provided with a rearwardly-extending arm *f*², influenced by a spring *f*³, which tends to rock the shaft *f* backward and to lift the routing-tools *e* off the work-pieces *B*.

In order to rock the shaft *f* forward and lower the tools into operative engagement with the work-pieces, the shaft *f* is provided with a second arm *f*⁴, adapted to be engaged by a cam *g*, formed on one end of a curved lever *g'*, pivoted to frame *a* at *g*². The other end of the lever *g'* is connected to a treadle *h* by rod *h*'. Thus by depressing the treadle the cam *g* will, by engaging arm *f*⁴, tilt the rock-shaft forward against action of spring *f*³, and thus force the routing-tools against and into the work-piece, according to the degree of pressure placed upon the treadle.

The depth to which the routing-tool may be introduced may be regulated by an adjustable stop *i*, that limits the play of arm *f*⁴.

The operation of the machine will be readily understood. The pattern and work-pieces being adjusted, the routing-tools are lowered upon the latter by pressure upon the treadle *h*. The handle *d'* is now manipulated to guide the tracing-tool *d* over the pattern and to impart a corresponding motion to the table *c*, and consequently to the work-pieces *B*. Thus the latter are guided underneath the rotating routing-tools *e*, and the design of pattern *A* is reproduced upon the work-pieces. When the operation is completed, pressure upon the treadle is removed, so that the spring *f*³ is free to rock the shaft *f* backward and cause the routing-tools to clear the work-pieces.

It will be seen that in my improved machine routing-work may be quickly and accurately executed, that the machine may be

readily driven and manipulated, and that the depth of the groove cut into the work-piece is under the constant control of the operator.

What I claim is—

5 In an engraving-machine, the combination of a freely-movable table, with a tracer movable therewith, a rock-shaft extending across the table, a routing-tool having a bearing that is mounted upon the rock-shaft, a spring 10 adapted to rock the shaft backward, an arm depending from the rock-shaft, a cam adapted

to engage said arm and to rock the shaft forward, and a stop for limiting the movement of the rock-shaft, substantially as specified.

Signed by me at New York city, county and 15 State of New York, this 7th day of August, 1900.

WILLIAM S. EATON.
